ROCKING CHAIR

John A. Gale, 978 E. Shady Lane, Wayzata, Minn.

Filed May 6, 1963, Ser. No. 74,748

Term of patent 14 years

(Cl. D15—6)

Fig 5

Fig 6

Fig 7

Fig 8

Fig 9

FIG. 1 is a perspective view of a rocking chair embodying my new design;

FIG. 2 is a front elevational view thereof;

FIG. 3 is a rear elevational view thereof;

FIG. 4 is a side elevational view thereof. The side not shown is the same in appearance as the side shown.

FIG. 5 is a top plan view thereof;

FIG. 6 is a bottom plan view thereof;

FIG. 7 is a vertical cross sectional view of FIG. 2 taken approximately along line 7—7 and looking in the direction of the arrows;

FIG. 8 is a detailed cross sectional view on an enlarged scale taken approximately along line 8—8 of FIG. 4 and looking in the direction of the arrows; and

FIG. 9 is a detailed cross sectional view on an enlarged

scale taken approximately along line 9—9 of FIG. 4 and looking in the direction of the arrows.

I claim:

The ornamental design for a rocking chair as shown and described.
